Inventor:-

William Bowling
By Higdon, Logan & Higdon, Atty's.

UNITED STATES PATENT OFFICE.

WILLIAM BOWLING, OF TROY, SOUTH DAKOTA, ASSIGNOR OF ONE-HALF
TO E. W. NEILSON, OF SAME PLACE.

PUZZLE.

SPECIFICATION forming part of Letters Patent No. 599,593, dated February 22, 1898.

Application filed September 28, 1897. Serial No. 653,407. (No model.)

To all whom it may concern:

Be it known that I, WILLIAM BOWLING, of the city of Troy, Grant county, State of South Dakota, have invented certain new and useful 55 Improvements in Puzzles, of which the following is a full, clear, and exact description, reference being had to the accompanying drawings, forming a part hereof.

My invention relates to puzzles; and it consists of the novel construction, combination, and arrangement of parts hereinafter shown, described, and claimed.

Figure 1 is a top plan view of my improved game or puzzle. Fig. 2 is a cross-sectional view taken approximately on the line 2 2 of Fig. 1.

Referring by numerals to the accompanying drawings, 1 indicates a plate or disk, the same being preferably circular in plan view 20 and constructed with a vertically-arranged integral flange or wall 2, that extends around the entire edge of said plate or disk 1. Located in the upper edge of said wall or flange 2 is an annular recess 3, in which rests the 25 edges of a transparent plate or cover 4, the same being held in position by a ring 5, that extends around the entire edge of said plate 4 and covers said edge and the top of the flange or wall 2. Located upon the top surface 30 face of the plate 1 and in the exact center thereof is a raised block 6, in the form of a five-cornered star. Located directly in front of each point of this star is a segmental rib or flange 7, between the meeting ends of which 35 are left slight spaces, such as 8.

9 indicates triangular blocks that extend outwardly away from each one of the segmental flanges or ribs 7, and when so positioned said triangular blocks 9 form a five-pointed star. Slight spaces, such as 10, are left between the inner corners of these triangular blocks 9, said spaces 10 being in direct alinement with the space 8 left between the ends of the segmental ribs or flanges 7.

45 Formed integral with the outer points of the blocks 9 are blocks 11, in the form of five-pointed stars, in the centers of which are formed circular recesses 12. Communicating with said recesses 12 and extending the entire length of the blocks 9 are passage-ways 50 13, the same communicating with the space

in which the center star 6 is located, directly opposite the segmental walls or flanges 7. It is essential that the stars 11 be differently colored or marked. The reason for this differential coloring or marking will be herein-after made plain.

14 indicates a series of spherical bodies of such a size that they will readily pass through the spaces 8 10 and through the passage-ways 60 13. It is essential that there be as many of these spherical bodies 14 as there are stars 11, and said spherical bodies 14 are differentially colored or indicated to correspond with the differently colored or indicated stars 11. 65

Before proceeding with the operation or manipulation of my improved game or puzzle it may be stated that the center star 6 and the circle composed of the segmental ribs or flanges 7 are intended to represent the sun. 70 The spherical bodies 14 represent a series of planets, and the recesses 12 in the stars 11 represent the orbits of said planets. The spherical bodies 14 are located at random upon the surface of the plate 1, and the operator or operators playing the game are required to so manipulate the casing of the game or puzzle as that the spherical bodies 14, representing the planets, will be located in their corresponding recesses 12, representing 75 the orbits of said planets. Said bodies 14 being spherical, they will easily roll over the surface of the plate 1 and readily pass between the spaces 8 and 10. When each one of the spherical bodies 14 is located in its 80 proper recess 12, the game is played and the puzzle solved.

By designating the spherical bodies 14 as "planets" and the center star 6 as the "sun" the game or puzzle will be found instructive, as 90 well as entertaining, as certain features regarding the planets and sun will be suggested to the mind of the operator.

The plate 1 and various blocks located thereon may be constructed of wood, metal, or 95 papier-mâché, or of any suitable material.

I claim—

1. A game or puzzle, comprising a suitable casing, a transparent cover for said casing, a star located upon the surface of and at the 100 center of said casing, segmental ribs or flanges directly opposite the points of said star, tri-

angular blocks located directly in front of said segmental ribs or flanges and constructed with passage-ways extending their entire length, blocks in the form of stars located at 5 the points of said triangular blocks and constructed with recesses in their centers communicating with the longitudinal passage-ways, and a series of spherical bodies adapted to traverse the passage-ways and be located 10 in the recesses, substantially as specified.

2. In a game or puzzle, blocks in the form of a five-pointed star so located as that a space is formed between said blocks, a star located within said space and surrounded by 15 a series of segmental flanges or ribs, a series of blocks in the form of stars located at the points of the first-mentioned blocks and constructed with recesses in their centers that communicate with passage-ways formed in 20 the first-mentioned blocks, and a series of spherical bodies adapted to pass through the spaces, traverse the longitudinal passage-ways and be located in the recesses, substantially as specified.

3. A game or puzzle, comprising a suitable 25 casing, a transparent cover for said casing, a star located upon the surface of and in the center of said casing, a series of segmental flanges or ribs surrounding said center star, a series of blocks constructed with longitudinal 30 passage-ways extending outwardly from the ribs or flanges in the form of a five-pointed star, blocks in the form of five-pointed stars located on the ends of said first-mentioned blocks and provided with recesses in their 35 centers that communicate with the longitudinal passage-ways, said last-mentioned blocks being differentially colored or indicated, and a series of differentially-colored spherical bodies that are adapted to be located in the 40 recesses in said differentially-colored blocks, substantially as specified.

In testimony whereof I affix my signature in presence of two witnesses.

WILLIAM BOWLING.

Witnesses:

EDMUND SITZER,
E. W. E. SITZER.
